INTERMITTENTLY-OPERATING ELECTRIC REGULATOR.

Application filed April 22, 1926, Serial No. 103,695, and in Sweden April 3, 1925.

Our invention relates to regulators for dynamo-electric machinery and more particularly to the type where the regulating is effected by intermittently short-circuiting a portion of a circuit, for instance containing a field resistor. The regulating may be applied to voltage, current, speed, or any other quantity of the machinery capable of being regulated in an analogous manner.

10 One object of our invention is to provide a regulator which is very light, handy and simple in construction.

Another object of our invention is to provide a regulator capable of directly (without 15 the use of an intermediary relay) controlling larger currents than has been possible heretofore.

The intermittently acting regulators as heretofore constructed generally comprise an oscillating armature carrying a contact and another armature supporting the pivot of oscillation for the former. The latter armature is actuated by a coil energized according to the quantity to be kept constant (for 20 instance the voltage of a main generator), while the former armature is actuated by a coil energized by a quantity controlling the former (for instance the voltage of an exciter). The latter quantity oscillates about 25 a medium value which is, however, not constant but depends on certain factors (for instance the load on the main generator). For this reason, the medium position about 30 which the first-named armature oscillates cannot be constant, and therefore the pivot of oscillation must also be movable. All 35 these circumstances result in a rather complicated construction and also in a rather hazardous operation of the contacts which 40 makes it impossible for these to control comparatively large currents.

According to our present invention, a single movable member is employed which oscillates around a stationary axis and carries 45 one of the contacts while the other contact is stationary. The said oscillating member is acted upon by the regulated quantity (e. g. main generator voltage) as well as by the 50 quantity oscillating in value, but the action of the former, when normal, is compensated for instance by a spring, and the mean value of the latter is compensated by electrical means which shall be described hereinafter. In this way, the oscillating member can be

made very light, and particularly by causing 55 it to swing in mechanical resonance with the electrical impulses the latter may be very weak and still sufficient to keep the regulator in operation. The swinging member 60 preferably carries no iron parts but only coils cooperating with stationary iron parts.

In order that our invention will be more readily understood, we have illustrated a preferred form thereof diagrammatically in the accompanying drawing, Fig. 1 being a 65 diagram of connections of the apparatus showing also a few mechanical details, Fig. 2 is a geometrical reproduction of the variation of the main quantities determining the 70 operation of the regulator, shown as a function of time, and Fig. 3 is a view showing a detail of construction.

Referring to Fig. 1, 11 is the armature winding and 12 the exciting winding of a main generator. The latter winding is fed 75 from an exciting generator having an armature winding 61 and an exciting winding 62. A resistor 63 connected in series with the latter is intermittently short-circuited by the regulator, whereby the voltage is regulated in a manner known in principle.

The regulator proper comprises an oscillating member 41 actuated by two magnetic fields having cores 31, 51. One of the fields is generated by a stationary winding 32 actuated by the voltage of the main generator. As in the example shown the latter is supposed to be an alternating current generator, it is connected to the winding 32 over a voltage transformer 13. The field generated by 80 the coil 32 acts on a coil 35 supported by the member 41, the said coil 35 being in series with the coil 32 and thus also actuated by a current proportional to the voltage of the main generator. The force acting upon the 85 coil 35 will thus be substantially proportional to the square of the generator voltage, and the winding directions of the coils are preferably such as to make this force 90 attractive.

The other field acting on the member 41 and having the core 51 is supposed to be constant and unidirectional and may for instance be generated by permanent magnetism. It acts on a coil 52 supported by the member 41 and fed in a manner characteristic to the invention which will be described later. The member 41 further supports a

- 2 contact 44 performing the aforesaid intermittent short-circuiting of the resistor 63. It swings in a knife-edge bearing 42, while the current is admitted by means of flexible conductors 47 and 48. The coils 35 and 42 can be conveniently supported by the member 41 as shown in Fig. 3, the frame of which member can serve as common return conductor for said coils.
- 10 The coil 52 is actuated by the voltage of the exciting generator, however not directly but in such a manner that the constant portion of the said voltage is "filtered away." This may be done in different manners, for instance by means of condensers, but a very handy and efficient way has been found to be to employ a transformer 53, the primary of which is connected to the terminals of the exciter over an ohmic resistor 54 while its secondary is connected to the coil 52. This transformer may also be provided with a tertiary winding 56 connected to a condenser 57 for delivering its magnetizing current. A corresponding winding with a condenser may be arranged also in any other suitable place, for instance on the core 31.
- 15 The member 41 is also actuated by a spring 43 counteracting the force between the coils 32 and 35. This force being supposed to be constant, as the regulator is intended to regulate upon constant voltage, the member can normally be considered to be actuated only by the oscillating force set up by the coil 52 in the constant magnetic field, by the unbalanced spring force caused under oscillation (when the spring is alternately stretched and contracted), and in some cases, if it is not counterbalanced with respect to its axis, by gravity. All these
- 20 forces are more or less accurately harmonic in nature and thus will cause a harmonic swinging of the member 41. What has a tendency to disturb this harmonic swinging is practically only the contact pressure, but by arranging the movable contact in some suitable manner also this disturbing action may be considerably reduced. A suitable arrangement of the movable contact has been found to be to suspend it in a hinge 46 practically coaxial with the knife-edge bearing 42 by a comparatively rigid member 45 and connect the latter to the member 41 by one or more weak springs 49. In this way, it is possible to avoid any sliding at the contacts which is objectionable in this apparatus. If the member 41 is balanced around its axis, two contacts balancing each other are also preferably employed.
- 25 The general manner of operation of the apparatus shall now be described, reference being had particularly to Fig. 2 of the drawing. The curve *s* represents the path of the member 41 and the curve *v* its velocity, both as functions of time. As long as the voltage of the main generator is constant, these will

be practically sine-shaped. By reason of the decidedly elastic connection between the member 41 and the movable contact or contacts, the latter will rest against the corresponding stationary contact or contacts 70 during practically one half of each cycle of oscillation of the member 41. The semi-cycles corresponding to closed contacts are marked by full-drawn, the semi-cycles corresponding to open contacts by dotted portions of the curve *s*. During the former semi-cycles, the exciter voltage (the variable portion of which is represented by the curve *E*) rises along a negative exponential curve, during the latter it sinks along a corresponding curve. As the exciter is preferably intended to operate on the straight portion of its magnetizing curve, the falling and rising branches of the curve *E* are symmetrical. If the circuits through the transformer were entirely non-inductive and the transformer itself free from magnetic leakage, the current through the coil 52 would follow practically the same curve as the voltage *E*, but on account of the inductance the real current *I* becomes more or less displaced in phase from the voltage and in the same time its curve obtains a more rounded shape. At any rate, it obtains a component in phase with the velocity *v*, such a component being just required for compensating the damping by friction and the like which is always more or less proportional to the velocity. The mechanical characteristics of the member 41 should preferably be such that it will swing practically in resonance with the electric impulses.

When the voltage of the main generator is changed by some reason, for instance a change in load, the above-described quasi-stationary conditions are disturbed. The force between the coils 32, 35 and that exerted by the spring 43 no longer keep each other in equilibrium, but either of these (depending on whether the voltage is raised or lowered) becomes predominant. As the member 41 is very light compared with these forces, it will instantly stop its motion and come to rest in one of its end positions, corresponding to open or closed contacts. The voltage of the exciter generator will then be very rapidly lowered or raised, until the voltage of the main generator is restored to its normal value, when the member 41 resumes its harmonic oscillation. It is to be noted, that the time intervals corresponding to open and closed contacts will still be equal, this condition corresponding to constant (high or low) value of the exciter voltage (as long as the machine operates on the straight portion of its magnetizing curve), while different intervals of closed and open contacts would correspond to a time variation of the exciter voltage. The only difference caused in Fig. 2 when the

exciter voltage is made higher or lower, is that the branches of the curve E will be higher and steeper and the amplitude of the curve I correspondingly larger.

5. Instead of using a separate transformer between the exciter and the coil 52, the latter may be connected to an extra winding on the field of the exciter. Instead of directly short-circuiting the resistor 63 by means of 10 the contacts 44 the said short-circuiting may be effected by an intermediary relay.

We claim as our invention:

1. In regulating systems for dynamo-electric machinery, an oscillating member carrying electromagnetic means responsive to the 15 action of the quantity to be regulated, contact means carried by said oscillating member and adapted to short-circuit a portion of an electric circuit, electromagnetic means 20 carried by said oscillating member and responsive to the action of an electric quantity altered by said short-circuiting and means for compensating the action, upon said oscillating member, of a certain portion of the 25 quantity to be regulated and of the quantity altered by said short-circuiting.

2. In regulating systems for dynamo-electric machinery, a member capable of oscillating about an axis, electromagnetic means carried 30 by said member and responsive to the action of the quantity to be regulated, a spring connected to said oscillating member and normally compensating the action of said electromagnetic means, contact means 35 carried by said oscillating member and adapted to short-circuit a portion of an electric circuit, electromagnetic means carried by said oscillating member and responsive to the action of an electric quantity altered by 40 said short-circuiting, and means for compensating the action, upon said oscillating member, of the mean value of said last-mentioned electric quantity.

3. In regulating systems for dynamo-electric machinery, a member capable of oscillating about an axis, electromagnetic means

carried by said member and responsive to the action of the quantity to be regulated, other electromagnetic means carried by said member and serving to maintain it in oscillation, 50 contact means carried by said oscillating member, an electric circuit a portion of which is adapted to be bridged over by said contact means so as to alter the conditions therein, and inductive electric connection between said circuit and said other electromagnetic means carried by the oscillating member 55 permitting only the periodic variations but not the mean value of the electric quantities of said circuit to affect said oscillating member.

4. In regulating systems for dynamo-electric machinery, a main generator, an exciter therefor, a resistor in the field circuit of said exciter, an oscillating regulator member, 60 contacts controlled by said member and adapted to intermittently short-circuit said resistor, electromagnetic means carried by said oscillating member and responsive to an electrical characteristic of said main generator, a transformer connected on its primary side to the terminals of said exciter and electromagnetic means carried by said oscillating member, responsive to the secondary current of said transformer. 70

5. In electric regulators adapted to operate by intermittently short-circuiting a portion of an electric circuit, an oscillatory member, contact means for said short-circuiting carried thereby, two coils adapted to be fed by 80 different circuits carried by said oscillatory member, stationary magnet cores adjacent to each of the paths of said coils, and means for maintaining, in one of said cores, a constant field, and in the other core a field proportional to the current traversing the coil moving adjacent thereto. 85

In testimony whereof we have signed our names to this specification.
